UNITED STATES PATENT OFFICE.

JOSEPH PEDERY, OF SPRINGFIELD, MASSACHUSETTS.

STOPPING MECHANISM FOR WIRE-WINDING MACHINES.

1,363,051.

Specification of Letters Patent. Patented Dec. 21, 1920.

Application filed December 16, 1919. Serial No. 345,178.

To all whom it may concern:

Be it known that I, JOSEPH PEDERY, a citizen of the United States, and resident of Springfield, in the county of Hampden and State of Massachusetts, have invented new and useful Improvements in Stopping Mechanism for Wire-Winding Machines, of which the following is a specification.

My invention relates to stopping mechanism, the invention being more particularly related to an improved mechanism having an automatic character for use in connection with wire winding machines, wire drawing machines and the like.

A main object of the invention is the provision of a mechanism of the kind specified, adapted automatically to unclutch or throw out of operative engagement the take-up mechanism of wire winding or drawing machines, whenever the wire strand becomes either tangled, knotted, or broken.

Another object of the invention is the provision of a mechanism of this character embodying coöperating means for automatically locking certain of the parts in the relative positions they occupy when the unclutching action is effected.

A further object is the provision of mechanism, embodying the foregoing features, which is of simple, compact and inexpensive construction, and which includes means by which it may be actuated manually as well as automatically.

Other objects and advantages will appear in the following specification and the novel features of the mechanism will be particularly pointed out in the appended claims.

My invention is illustrated in the accompanying drawings forming part of this application in which:—

Figure 1 is a view in perspective of the preferred form of casing, designed to hold my improved mechanism as well as the wire take-up mechanism.

Fig. 2 is a vertical cross section, taken centrally through the casing, and more specifically in the direction of line 2—2 of Fig. 3.

Fig. 3 is a vertical cross section, taken on the line 3—3 of Fig. 2.

Fig. 4 is a perspective view of the wire guide block with its pulley.

Fig. 5 is a cross section, looking in the direction of the line 5—5 of Fig. 2.

Fig. 6 is a detail view of the gage or die

block; while Fig. 7 shows a cross section on the line 7—7 thereof.

Fig. 8 is a horizontal cross section, showing the parts as they appear when looking in the direction of the line 8—8 of Fig. 2.

Figs. 9 to 14 inclusive are various views of the clutch, shown in successive phases of operation. Of these views, Figs. 9, 11, 12 and 14 are cross sections, Fig. 11 being taken on the line 11—11 of Fig. 10, and Fig. 14 on the line 14—14 of Fig. 13. Fig. 10 is a longitudinal section, and Fig. 13 a side elevation.

In carrying out my invention, I preferably make use of a box-like casing consisting of parallel front and back plates 15 16, parallel side plates 17 18, and parallel bottom and top plates 19 20. Through the center of the top 20 is cut a circular aperture 21, in which works a clutch element 22, fast on the vertical shaft 23 having bearing in a block 24, bolted to the underneath side of the said top, and also in a central bracket 25, rising from the bottom 19. Formed to have clutching engagement with the element 22 is the axially projecting hub portion 26 of the flanged take-up or pulley 27, loosely mounted upon the shaft 23 above the top plate 20. Provision for effecting the clutching engagement may be made for instance by providing the element 22 with a rack tooth 28, which is adapted to enter a corresponding recess cut in the hub portion. Unclutching action is effected by elevating the take-up until the hub portion is clear of the rack tooth; and means through which to accomplish this both automatically and manually will be hereinafter described.

Journaled in the central bracket 25, as well as in other brackets 29 alined therewith is a horizontal driving shaft 30, which projects through an opening 31 provided in the casing side 18, so that the means (not shown) for rotating the shaft may be applied exteriorly of the casing. Movement is imparted to the vertical shaft 23 from the shaft 30 by means of the engaged bevel gears 32 and 33.

As best illustrated in Figs. 1 and 2, there is bolted to the front and top plates 15 and 20, an angular plate 34 constituting the rear plate for a casing including parallel side plates 35 36, a downwardly inclined bottom 37, a front plate 37', and confronting top strips 38 upon and between which is ar-

ranged a plate 39 having movement toward and away from the take-up. With this slide plate 39 is cast an operating handle 40, a front upstanding flange 41, and a rear 5 channel-shaped holder 42 for operatively receiving a gage block 43, provided with eyes or reducing dies as 44 through which is drawn the wire to be wound upon the take-up. The gage block 43 is shiftable either to 10 the right or to the left, and the eyes or dies therein differ in size so as to make provision for handling wires of different gages.

Depending centrally from the slide 39 is a vane 45, against the inner side of which 15 abuts the short arm of a bell crank lever 46, tiltable on a fixed pivot 47, carried between the lugs 48, outwardly projecting from the plate 34. The long arm of the bell crank lever projects through suitable openings into 20 the main casing, where, by means of slot and pin structures 49 and 50, it has operative connection with a bar 51, which extends downward and terminates in an angle 52, bifurcated as shown to operatively receive the end of an arm 52', projecting at right-angles from a shipping lever shaft 54, to be presently described.

Acting on the short arm of the bell crank lever so as to maintain the slide 39 normally 30 in its outermost position is a push spring 55. Movable on the fixed pivot 47 alongside the bell crank lever is a lever 56, which projects through a suitable opening provided in the front plate 37' and terminates in a 35 reduced portion 57. With this lever is also formed a rearwardly curved arm 58 having a laterally bent lug 59 (Fig. 5) adapted to engage the short arm of the bell crank lever. Engaged upon the reduced end 57 and ad-

40 justable thereon by means of a set screw 60 is an elongated block 61, provided with a grooved wire pulley 62, one side of this block having an opening 63 to permit of the lengthwise insertion of a strand of wire, 45 said opening being normally closed by a flexed spring 64, pinned to the block at 65. As shown in Fig. 2, a wire strand as 66, to be coiled on the take-up, is engaged under the pulley 62 of block 61, and then over 50 an idle pulley 67, carried by bracket 68, which projects upwardly at an angle from the front plate 37' and at such elevation that the strand is held in line with the selected gage block 44 through which it is to pass.

55 The front slide flange 41 has a notch 69, and the channel-shaped piece 42 has central openings 70 through which the strand passes. On opposite sides of the path of the strand, posts as 71 rise from the angle plate 34 to 60 serve as guides for the strand. Should the wire strand become kinked or knotted so that it cannot be drawn through the block 61 under the pulley 62, the lever 56 will be elevated in an obvious manner, tilting the bell crank lever 46 inwardly upon its axis

and turning the shaft 54 a distance. Should the wire strand stick in the gage block or become kinked or knotted in front of the same, an equivalent result is obtained; the bell crank lever in this case, however, being tilted by the vane 45 as the slide is drawn toward the take-up under the pull of the wire strand.

The shaft 54, which is turned a distance through the movement toward the take-up 75 of either lever 57 or slide 39 as described, is journaled in the lateral lugs 72 and 73 of the floor bracket 74. Fast with the shaft 54 is a shipping lever 75, which works in the annular groove 76 of the clutch part 77, 80 mounted on the driving shaft 30, said clutch part being slotted at 78 so as to have limited axial movement on a pin 79 by which it is held to said shaft. The face of this clutch part is formed with an outwardly 85 beveled peripheral lug 80 with an axially directed shoulder 81. The bottom bracket 74 has an upstanding part 82, which terminates spacedly from the shaft 30 so as to form a guide arm against which bears the 90 loose clutch part 83, held in position on the driving shaft by a collar 84 pinned thereto at 84'. Said clutch part 83 carries a pin 85 close to the driving shaft so as to clear the guide arm but in position to be engaged by 95 the lug shoulder 81 when the clutch part 77 is thrust over by the shipping lever under the turning of the shaft 54. When, through the engagement of the shoulder 81 with the pin 85, the clutch part has been turned the 100 desired distance as shown in Fig. 14, the guide plate 82 engages the lug 80 and thrusts the part 77 over, disengaging the shoulder from the pin.

Pivoted connected at 86 with the clutch 105 part 83 is a link 87, whose upper end is connected at 88 with a lifting lever 89, fulcrumed at 90 to a bracket 91, secured to the rear plate 16. The forward end of this lifting lever is reduced at 92 to work in an 110 angled slot 93 cut through the front plate 15.

Depending from the block 24 are the hangers 94, carrying a rock shaft 95, to the outer ends of which are secured the rocker 115 bars 96, whose inner ends extend into the plane of the vertical shaft 23—one on each side thereof. Rising from the inner ends of these bars are uprights 97 carrying rollers 98 engageable with the take-up pulley. One 120 of the rocker bars 96 is connected at its forward end with the lifting lever 89 by a link 99, so that when the lifting lever 89 is drawn down by the turning of the clutch part 83, the take-up pulley will be raised from the 125 rack tooth of the clutch element 22. Obviously, the movement of the clutch part 83 is limited by the engagement of the reduced lever end 92 with the bottom wall of the slot 93; and immediately said bottom wall is 130

reached, a spring 100, connecting the lifting lever with the side plate 17, draws the reduced end 92 into the horizontal end of the slot 93, whereupon the parts are securely 5 locked with the take-up pulley in elevated position.

From the foregoing description, taken in connection with the accompanying drawings it will be understood that each time the 10 bell crank lever 46 is tilted as hereinbefore described, whether by the slide 39 or by the lever 56, the take-up pulley 27 will be automatically elevated from its clutch to ride loosely upon its shaft. It will also be understood that the slide 39 may be actuated 15 at will by means of the handle 40; and further that the lifting lever 89 is always free to be operated independently of its automatic operation by the slide 39 or lever 56.

Having thus described my invention, what I claim is:—

1. In a stop mechanism of the kind described, the combination with a casing, a driving shaft therein, a driven shaft projecting from the casing and provided with a clutch element, a take-up pulley having means to coöperate with said clutch element, a fulcrumed frame actuable to raise the take-up pulley from its clutch, a fulcrumed 25 lifting lever having connection with said frame whereby to actuate it, said lifting lever projecting from the casing and being manually operable, means for automatically operating said lifting lever including a 30 gage through which the wire strand passes and arranged to be actuated by the knotting or kinking of the wire strand, coöoperating clutch parts on said driving shaft, a connection between one of said parts and the 35 lifting lever for actuating the latter when the clutch is thrown "in," and means including a shipping lever for throwing the clutch "in" upon the actuation of said gage.

2. In a stop mechanism of the kind described, the combination with a main casing and an auxiliary casing having communication therewith, a driving shaft and a driven shaft disposed in the main casing, said driven shaft projecting from the casing and provided with a clutch member, a take-up pulley having means to coöperate with the clutch member, a fulcrumed frame actuable to raise the take-up pulley from the clutch member, a fulcrumed lever for 45 actuating said frame, the same projecting from the casing for manual operation, means for automatically actuating sail lifting lever comprising coöoperating clutch parts on the driving shaft, one of the clutch parts having a connection with the lifting lever whereby to actuate the 50 same when the clutch is thrown "in," a bell crank lever pivoted in the auxiliary casing and extending into the main casing, movable devices operatively arranged in the

auxiliary casing and through which the wire strand must pass on its way to the take-up pulley, each of said movable devices being actuable when the wire strand is tangled or otherwise cannot pass freely therethrough, 70 each of said movable devices being arranged to tilt said bell crank lever, and means including a shipping lever for throwing said driving clutch "in" when the bell crank lever is tilted.

3. In a stop mechanism, a driving shaft and a driven shaft, both continuously rotated, a clutch element on the driven shaft, a take-up pulley having means to coöperate with the clutch member, a fulcrumed frame 80 for raising the take-up pulley out of engagement with the clutch member, a fulcrumed lever for actuating said fulcrumed frame, coöperating clutch parts on the driving shaft, a connection between the fulcrumed lever and one of the clutch parts whereby when the clutch is thrown "in" the fulcrumed lever will be actuated, a slide provided with a gage through which the wire strand is drawn, said slide being arranged for movement when free passage of the wire through the gage is prevented, a spring pressed bell crank lever arranged to be tilted by the movement of said slide, means controlled by the movement of 90 the bell crank lever for throwing the driving shaft clutch parts into engagement, and means for unclutching said parts immediately upon the actuation of the fulcrumed lever.

4. In a stop mechanism, a driving shaft and a driven shaft, both continuously rotated, a clutch element on the driven shaft, a take-up pulley having means to coöperate with the clutch member, a fulcrumed frame 105 for raising the take-up pulley out of engagement with the clutch member, a fulcrumed lever for actuating said fulcrumed frame, yielding means for drawing said fulcrumed lever into locked position upon its 110 actuation, coöoperating clutch parts on the driving shaft, a connection between the fulcrumed lever and one of the clutch parts whereby when the clutch is thrown "in" the fulcrumed lever will be actuated, a pivoted 115 lever provided with an arm, a spring pressed bell crank lever engaged with said arm, a block adjustable on the lever and through which the wire strand is drawn, said bell crank lever being tilted under the 120 tension of the drawn wire when the latter becomes tangled at the back, means controlled by the tilting of the bell crank lever for throwing the driving shaft clutch parts into engagement, and means for effecting 125 the unclutching of said parts immediately upon the actuation and locking of the fulcrumed lever.

5. In a stop mechanism, a driving shaft and a driven shaft, both continuously ro- 130

tated, a clutch element on the driven shaft, a take-up pulley having means to coöperate with the clutch member, a fulcrumed frame arranged to raise the take-up pulley 5 out of engagement with the clutch member, a fulcrumed lever for actuating said fulcrumed frame, yielding means for drawing said fulcrumed lever into locked position upon its actuation, coöperating clutch 10 parts on the driving shaft, a connection between the fulcrumed lever and one of the clutch parts whereby when the clutch is thrown "in" the fulcrumed lever will be actuated, a pivoted lever provided with an 15 arm, a spring pressed bell crank lever engaged with the said arm, a block adjustable on said lever and through which the wire strand is drawn, a slide provided with a

gage through which the wire strand is also drawn, said slide being held in engagement 20 with the bell crank lever by the tension of the wire strand, said bell crank lever being tilted under the tension of the drawn wire strand when the latter becomes tangled or otherwise held against passage either at 25 the block or at the gage, means controlled by the tilting of the bell crank lever for throwing the driving shaft clutch parts into engagement, and means combined with said clutch parts for effecting the unclutching 30 of said parts immediately upon the actuation and locking of the fulcrumed lever.

In testimony whereof I have signed my name to this specification.

JOSEPH PEDERY.
